UNITED STATES PATENT OFFICE.

FRANZ XAVER HALLINGER, OF HAMBURG, GERMANY.

METHOD AND MEANS FOR DRAINING THE GROUND FOR SUBAQUEOUS EXCAVATIONS.

1,204,977.

Specification of Letters Patent.

Patented Nov. 14, 1916.

Application filed March 29, 1916. Serial No. 87,544.

To all whom it may concern:

Be it known that I, FRANZ XAVER HALLINGER, a subject of the King of Bavaria, and resident of No. 104/106 Steinstrasse, Hamburg, in the Empire of Germany, have invented a new and useful Method and means for Draining the Ground for Subaqueous Excavations, of which the following is a specification.

10 The present invention relates to an improved method and means for draining the ground for subaqueous excavations. Inside a tower to be erected at the bottom of the river or the like, which tower is open at its 15 lower end and corresponds to the width of the ditch to be excavated. The water is completely driven out by compressed air and at both sides of the ditch to be excavated pile planking is driven over which a water 20 tight cover is constructed. Subsequently inside the space bordered by or between the pile planking, a tunnel or adit having a previous wall is run, toward which tunnel or adit the ground-water flows so that it can be 25 pumped above ground.

In the annexed drawings is shown by way of example one mode of carrying into practice this invention.

Figure 1 shows the improved means for 30 draining the ground for subaqueous excavations in vertical longitudinal section. Fig. 2 is a vertical transverse section.

Supposing an excavation is to be carried out below the bottom of a river, according 35 to the present invention a tower *a* is employed, which is open at its lower end and which corresponds to the width of the ditch to be excavated. This tower *a* is movable upon a trestle or framing *b*, which is 40 progressively constructed as the work proceeds. According to the depth of the water this tower *a* can be adjusted and fixed at a lower or higher elevation. In deep water, when the weight of the tower is not sufficient 45 to place the latter upon the bed or bottom of the river, additional weight is provided by means of cast iron blocks, lead, concrete or the like.

The tower *a* serves for the purpose of expelling or driving out by means of compressed air, the water down to the lower edge of the tower and, when required, still deeper. In the latter case it is advantageous to place clay or fine sand at the joint 55 of the lower edge of the tower with the bed or bottom of the river. The tower *a* fur-

ther serves for operating, by means of electric- or compressed air, pile drivers for driving pile planking *d* at both sides of the ditch to be excavated and for constructing 60 above this pile planking and in tight connection therewith, a water tight cover *e* at the bottom of the river.

Into the space bordered by the pile planking *d* and covered by the cover *e*, a small 65 tunnel or adit *f* is run below the bottom or sole of the structure to be subsequently erected. The wall or lining of this tunnel or adit is pervious or perforated or contains tubes, which allow the ground-water to flow 70 into the tunnel or adit, so that it can be conveyed above ground by means of suitable pumps. Thus the structure to be erected above the tunnel or adit between the pile planking can consequently be constructed in 75 a dry ditch without applying compressed air.

What I do claim as my invention and desire to secure by Letters-Patent is

1. Improved method for draining the 80 ground for subaqueous excavations, consisting in erecting a tower at the bottom of the river or the like above the place destined for the structure to be permanently constructed, said tower being open at its lower end and 85 corresponding to the ditch to be excavated, consisting further in driving the water completely out of the tower by compressed air, in driving pile planking at both sides of the ditch to be excavated, in constructing a 90 water tight cover above the pile planking at the bottom of the river in running a tunnel into the space between the pile planking, said tunnel having a pervious wall, and in finally pumping the water collecting inside 95 the tunnel or adit above ground.

2. A method for draining ground for subaqueous excavations consisting in erecting a caisson extending to the bottom of a body of water, in removing the water from within the caisson, in separating the earth within the caisson and to be excavated by partitions extended into the ground, in covering the earth between said partitions with a substantially 100 water-proof covering, and in providing a tunnel having a pervious wall for draining the earth between said partitions.

3. A method for draining ground for subaqueous excavations consisting in separating, by partitions extended into the ground, the 110 earth to be excavated, in covering the earth between said partitions with a substantially

water-proof covering, and in providing a draining adit for draining the earth between said partitions.

4. A method for draining ground for sub-
5 aqueous excavations, consisting in erecting a caisson at the bottom of a body of water, in removing the water within the caisson, in driving piles for partitioning the portions of the earth to be excavated, in covering the
10 portions of earth between said partitions

with a substantially water-proof covering, and in providing an adit for draining the earth between said partitions.

In witness whereof I have hereunto signed my name this 3rd day of December, 1915, in ¹⁵ the presence of two subscribing witnesses.

FRANZ XAVER HALLINGER.
